ATTORNEY.

UNITED STATES PATENT OFFICE.

MORRIS ROBERTS, OF PHILADELPHIA, PENNSYLVANIA, ASSIGNOR OF ONE-HALF TO GEORGE W. HOPKINS, OF SAME PLACE.

WINDOW-SCREEN.

SPECIFICATION forming part of Letters Patent No. 293,277, dated February 12, 1884.

Application filed September 8, 1883. (No model.)

To all whom it may concern:

Be it known that I, MORRIS ROBERTS, a citizen of the United States, residing in the city and county of Philadelphia, State of Pennsylvania, have invented a new and useful Improvement in Insect-Screens, which improvement is fully set forth in the following specification and accompanying drawings, in which—

10 Figure 1 is a horizontal section in line *x x*, Fig. 2, of an insect-screen embodying my invention. Fig. 2 is a face view of the screen. Fig. 3 is a vertical section in line *y y*, Fig. 2.

15 Similar letters of reference indicate corresponding parts in the several figures.

My invention consists of an insect-screen the frame whereof is strong and durable, as will be hereinafter described.

Referring to the drawings, A represents an insect-screen formed of two frames, A', each formed of top piece *a*, bottom piece *b*, side piece, *c*, stile *d*, horizontal top and bottom pieces *e*, and netting *f f*, the pieces *e* and pieces *a b* being on opposite faces of the frame. 20 The side of each stile is grooved, as at *g g*, near the upper and lower ends, the said grooves being opposite to each other, and the top and bottom pieces *e e* are fitted in said grooves, so as to be secured and slide therein 25 during the opening and closing motions of the screen. It will be seen that each stile has secured to it on one side the ends of top and bottom pieces *e e*, and opposite to the places of the attachment of said pieces the grooves *g*,

thus avoiding the central piercing of the stiles, 35 and providing a brace for each side of the stiles, whereby the connection of the frames one with another is vastly strengthened, and the frames are prevented from being bent apart between the stiles. The location of the pieces 40 *e e* is preferably at places adjacent to the top and bottom pieces *a b* of the frames A', where the fingers are generally applied in carrying the screen; hence the pressure of the fingers on the netting is restrained by the pieces *e e*, so 45 that the netting is prevented from being bulged in at the places indicated, it being evident that where there are pieces passed centrally through the stiles the netting has no support 50 thereon, and hence may be fractured and pierced by the fingers or torn from their places of attachment with the pieces *a b* of the frame, all of which is avoided by my construction.

Having thus described my invention, what I claim as new, and desire to secure by Letters 55 Patent, is—

An insect-screen consisting of frames each having top and bottom horizontal pieces, a side piece, a grooved stile, and additional horizontal pieces which are secured to the 60 frame on the face opposite to said top and bottom pieces, substantially as and for the purpose set forth.

MORRIS ROBERTS.
